DESIGN FOR A YARN REEL

John D. O'Neill and Alexander H. Sullivan, St. Louis, Mo., assignors, by direct and mesne assignments, of one-third to Gates A. Halfin, St. Louis, Mo., and two-thirds to said Sullivan

Application February 21, 1938, Serial No. 75,298

Term of patent 3½ years

To all whom it may concern:

Be it known that we, John D. O'Neill and Alexander H. Sullivan, citizens of the United States, residing at St. Louis, Missouri, have invented a new, original, and ornamental Design for Yarn Reel, of which the following is a specification, reference being had to the accompanying drawing, forming part thereof.

Figure 1 is a perspective view of the yarn reel showing my design;

Figure 2 is a top view; and

Figure 3 is a side view thereof.

The design is characterized by a base comprising a relatively narrow border and elongated ungulate spokes extending to the center where a vertical rod carries transversely disposed arms terminating in upturned hooks.

We claim:

The ornamental design for a yarn reel, substantially as shown and described.

ALEXANDER H. SULLIVAN.

JOHN D. O'NEILL.
